ELECTRON DISCHARGE DEVICE

Walter Louis Krahf, Montclair, N. J., assignor,
by mesne assignments, to Arcturus Develop-
ment Company, Newark, N. J., a corporation
of Delaware

Application February 12, 1931. Serial No. 515,237

8 Claims. (Cl. 250—27.5)

This invention relates to electron discharge de-
vices, and more particularly to the assembly of
the electrodes therein.

The objects of the invention are to provide an
improved assembly structure of electrodes which
will obtain rigidity of parts; proper cooperation
between the parts; maintenance of desired tube
characteristics; avoidance of current leakage so
far as possible; ready assembly of the parts with
minimum operation; simplicity of construction
and conformity to required standards; and to
obtain other advantages and results as may be
brought out in the following description.

Referring to the accompanying drawing in
which like numerals of reference indicate similar
parts throughout the several views:

Figure 1 is a side elevation of an electrode as-
sembly shown mounted in an envelope broken
away to disclose the assembly; and
20 Figure 2 is a sectional view on line 2—2 of
Fig. 1.

In the specific embodiment of the invention
illustrated in said drawing, reference numeral 1
indicates an envelope, usually constructed of
25 glass and providing in the finished item an up-
standing stem 2 within the envelope and having a
press 3 by which a plurality of upstanding rods
are sealed-in, the lower ends of certain of the
30 rods being connected to prongs 4 exterior of the
envelope and carried as usual by a base 5 mount-
ed at the lower end of the envelope. This struc-
ture, as so far described, is common in the art
and may be varied in accordance with desired or
35 common practice.

As here shown, the sealed-in rods upstanding
from the press are all in a common plane, being
positioned in a row and the two extreme rods
40 6, 6 of the row are much longer than the other
rods, extending the full height of all of the elec-
trodes. Between the extreme rods 6, 6 are three
other rods, two of which, as 7, 7, are preferably
45 disposed symmetrically with respect to the lon-
gitudinal axis of the envelope and form support-
ing connections for the ends of a hair-pin fila-
ment 8. The third intermediate rod, disposed
between one of the filament rods and one of the
50 said extreme rods 6 constitutes a support 9 for
the lower end of a grid 10.

The electrodes utilized in the present construc-
55 tion of electron discharge device comprise in ad-
dition to the upstanding hair-pin filament 8, a
tubular cathode 11 which surrounds the hair-pin
filament and is heated thereby. Suitable insu-
lation, such as surface coating on one of the
55 parts is provided between the filament and cath-

ode so as to electrically separate the two parts
and prevent short circuiting of the filament.
Grid 10 is preferably of a cylindrical character
composed of a plurality of convolutions of a heli-
cally wound wire, the grid being coaxial with the 60
cathode and carried by a longitudinal rod 12
within the grid and to which each convolution
thereof is secured as by welding. Outside of the
grid is arranged a cylindrical anode 13, this part
also being coaxial with the grid and cathode. 65
The anode is preferably made of sheet metal
with the marginal ends of the metal brought to-
gether after forming the cylinder and extending
radially from the cylindrical portion as a longi-
tudinal flange 14 and with the extreme edge of 70
the flange encircling and secured to one of the
extreme upstanding rods 6.

The construction of the anode constitutes one
of the features of the present invention. It will
be noted that the anode provides a pair of ex-
tensions 15 at its upper end on opposite sides
of the cylindrical part of the anode, the upper
edges of these extensions forming upwardly fac-
ing shoulders. The lower end of the flange 14
extends below the lower edge of the cylindrical 80
portion of the anode, as at 16, and the lower
edge of this extension likewise provides a down-
wardly facing shoulder. Above and below the
anode, transverse to the axis thereof, are a pair
of parallel insulators 17—17, and these insulators
engage with their flat surfaces against the shoul-
ders provided by the extensions on the anode. 85
In order to hold the insulators assembled with
respect to the anode, the upper extensions 15
have small tabs or ears 18 extending through
the insulators and bent over at the upper side
thereof, as clearly shown in Fig. 2. The lower
extension 16 likewise has ears 19 projecting
through the lower insulator and bent over beyond
the surface thereof. It will therefore be ob-
served that the insulators are spaced from the
anode for a major portion of the end edges of
the anode. This is particularly true at the
bottom of the anode where the entire circum-
ferential edge of the cylindrical portion of the 90
anode is spaced from the insulator and the
only contact of the anode with the insulator at
the bottom of the anode is between the ex-
tension 16 of flange 14 off-set from the cylindri-
cal portion. This construction will accordingly
95 obtain a desired circulation and enable the gase-
ous contents of the envelope and residual gases
within the cylindrical anode to be very thorough-
ly removed and to be affected by "flashing" the
tube. It will be understood that it is common
100

105

110

practice in manufacture of electron discharge devices to provide a capsule 20 of magnesium or other material which is ultimately heated to higher temperature, or flashed for obtaining a combination with gases remaining in the tube to eliminate the same as gases. I have found that in order to fully accomplish this elimination of residual gases that the same must be eliminated from within the anode as well as elsewhere, and 10 I have therefore provided the cathode which is open at its end nearest the capsule and open particularly at its lower end to encourage the downward movement of the gases as the same become affected by the flashing of the magnesium or other material. I find this elimination of residual gases is further aided by utilization of a foraminous anode, and as herein shown, the anode may have its middle portion perforated by a plurality of holes 21. The holes 21 15 are preferably confined to a middle band of the anode, and above and below the band of perforations the anode may have a circumferential rib 22 for reinforcing the same.

Insulators 17-17 are for purposes of mounting 25 the several electrodes. As already described, the anode is secured to the insulators against extensions 15, 16 of the anode. Rod 6, supporting the anode, likewise extends through both of the insulators and similarly the opposite rod 6 extends 30 through both the insulators, thereby keeping the insulators from twisting with respect to each other and conversely the insulators maintain the rods in proper spaced position. The grid supporting rod 12 projects beyond the ends of 35 the grid through the two insulators, and consequently the grid is held in proper relationship to the anode. The cathode likewise extends through the insulators which have parts thereof engaging and centering the cathode. Accordingly, all 40 of the electrodes are positioned with respect to each other by the insulators.

It is desirable to maintain the insulators in 45 fixed parallel position. The upper insulator is secured by the plurality of ears 18, and in addition thereto a band connector 23 is attached to the end of the cathode projecting above the insulator, the band extending edgewise with respect to the insulator and passing around the projecting grid supporting rod out of contact therewith and toward the extreme rod 6. The insulator is 50 radially slotted so that this band connector may have a downwardly projecting portion passing through the slot and then extending toward and around the rod 6. The portion of the band which is above the insulator obviously holds the insulator down and the underlying portion of the band holds the insulator up.

At the bottom of the electrodes the insulator 55 17 is secured near one end portion, as by engagement between the extension 16 and ears 19. At the other end portion a band support 24 edge-wise with respect to the insulator surface is secured to the lower end portion of the grid supporting rod above the insulator, the band extending radially as far as its supporting rod, overlying the insulator and preventing the same from upward movement. In order to prevent the insulator from downward movement at this end, a wire bracket 25 is welded or otherwise secured to the extreme rod 6 immediately beneath the insulator, this bracket 25 constituting means for supporting capsule 20 heretofore referred to. It will accordingly be appreciated that both ends of this insulator are prevented from either upward or downward movement and are therefore

held equally spaced from the ends of the upper insulator so that the two insulators are always parallel and rigid.

By the construction here shown, it will be observed that all of the rods sealed in the press 80 constitute electric conductors, one of the extreme rods 6 being a conductor for the anode while the other extreme rod is a conductor for the cathode. The two symmetrically positioned middle rods 7-7 are conductors for the filament 85 or heater whereas the intermediate rod 9 is a conductor for the grid.

It is further to be understood that the present invention provides for assembly of the several electrodes independent of the sealed-in conductor 90 rods. The several electrodes are first assembled with respect to the insulators and then slid lengthwise onto the extreme rods 6-6 until finally the grid band 24 engages conductor rod 9 and cathode band 23 slips onto its rod 6. In 95 this position of parts the flange for the anode may then be welded to the rod 6, the ends of the filament may be welded to rods 7-7, bands 23 and 24 may be welded to their respective rods 6 and 9, and the assembly of electrodes is then 100 both mounted in position and electrically connected as required.

Obviously detail changes and modifications may be made in the construction and use of my improved electron discharge device without departing from the spirit or scope of the invention, 105 and I do not wish to be understood as limiting myself to the exact construction shown or described except as set forth in the following claims when construed in the light of the prior art. 110

1. An electron discharge device having in combination with a cathode and grid, a support rod offset from said cathode and grid, an anode having a portion thereof surrounding the cathode and grid and having another portion thereof extending laterally therefrom forming a flange, the outer margin of said flange portion encircling said support rod, one end of said flange having a length greater than the portion of the anode surrounding the grid and cathode, and 120 a plate engaged by and positioned cross-wise of the flange at the end thereof having the greater length thereby spacing the plate from the portion of the anode surrounding the cathode and grid. 125

2. An electron discharge device having in combination with a cathode and grid, a support rod offset from said cathode and grid, an anode having a portion thereof surrounding the cathode and grid and having another portion thereof extending laterally therefrom forming a flange, the outer margin of said flange portion encircling said support rod, the portion of the anode surrounding the grid and cathode having an extension at one end only projecting beyond 135 the end of said flange and a plate engaged by and positioned cross-wise of the said extension on the anode thereby spacing the plate from the non-extended portion of the anode.

3. An electron discharge device having in 140 combination with a cathode and grid, a support rod offset from said cathode and grid, a pair of insulatory plates transverse to the cathode receiving the end portions thereof, said support rod projecting through both of said plates, an 145 anode disposed between said plates and having dissimilar extensions at opposite ends thereof for engaging said plates.

4. An electron discharge device having in combination with a cathode and grid, a support rod 150

- offset from said cathode and grid, a pair of insulator plates transverse to the cathode receiving the end portions thereof, said support rod projecting through both of said plates, an anode disposed between said plates having a portion thereof surrounding the cathode and grid and having another portion thereof extending laterally therefrom forming a flange, said flange having an extension engaging one of the plates for holding the grid and cathode surrounding portions spaced from said plate. 5
5. An electron discharge device having in combination with a cathode and grid, a support rod offset from said cathode and grid, a pair of insulator plates transverse to the cathode receiving the end portions thereof, said support rod projecting through both of said plates, an anode disposed between said plates having a portion thereof surrounding the cathode and grid and having another portion thereof extending laterally therefrom forming a flange, said flange having an extension engaging one of the plates for holding the grid and cathode surrounding portions spaced from said plate, and 10 the opposite end of said surrounding portion having means for spacing the flange from the other plate. 15
6. An electron discharge device having in combination with a cathode and grid, a pair of sup- 20

- porting rods on opposite sides of said cathode and grid, an anode carried by one of said rods, an insulating plate at one end of the anode secured thereto, and means for securing said plate with respect to the other support rod. 80
7. An electron discharge device having in combination with a cathode and grid, a pair of supporting rods on opposite sides of said cathode and grid, an anode carried by one of said rods, an insulating plate at one end of the anode secured thereto, a grid connection engaging said plate for holding it against movement in one direction, and means on the opposite side of said plate for holding it against movement in another direction. 85
8. An electron discharge device having in combination with a cathode and grid, a pair of supporting rods on opposite sides of said cathode and grid, an anode carried by one of said rods, an insulating plate at one end of the anode secured thereto, a grid connection engaging said plate or holding it against movement in one direction, and a bracket secured to the rod on the opposite side of the plate from the holding portion of said grid connection so as to cooperate with the grid connection for preventing the plate from movement in either direction. 90
